UNITED STATES PATENT OFFICE.

OLOF OHLSON, OF NEWTON, MASSACHUSETTS, ASSIGNOR TO WALTHAM WATCH COMPANY, OF WALTHAM, MASSACHUSETTS, A CORPORATION OF MASSACHUSETTS.

MECHANICAL TIME-FUSE FOR PROJECTILES.

1,319,304.

Specification of Letters Patent.

Patented Oct. 21, 1919.

Application filed December 8, 1917. Serial No. 206,278.

To all whom it may concern:

Be it known that I, OLOF OHLSON, a citizen of the United States, residing at Newton, in the county of Middlesex and State of 5 Massachusetts, have invented new and useful Improvements in Mechanical Time-Fuses for Projectiles, of which the following is a specification.

My present invention has reference to 10 fuses for artillery shells and other explosive projectiles, and particularly to that type of fuse which is controlled entirely by mechanism so as to ignite the charge of the projectile after lapse of a predetermined time from the firing, or release otherwise, of the projectile or other container of the explosive charge. The main object of the invention is to furnish a fuse of this character which shall be certain to operate at the time set 15 for its operation; and in realizing this object I have provided certain novel elements and combinations having to do with the time mechanism, the regulating or setting means for such mechanism, a hammer and 20 trigger mechanism, a safety stop preventing the time mechanism from beginning to run until the desired instant, and improvements in the frame of the fuse by which the necessary strength and rigidity is secured 25 without excessive weight and complete freedom of motion is afforded for the necessary moving parts of the mechanism; all co-operating to cause or permit substantially exact running of the time mechanism and 30 prompt release of the firing hammer at the given instant, without disturbance by the forces acting upon the fuse while the same is carried by the shell in flight and at the moment of firing it from a gun. The invention 35 therefore consists in the various means and improvements by which my object is accomplished, and in the principles underlying such means and improvements, all as hereinafter set forth in detail and recited 40 in the claims.

The present application is in the main a continuation of my earlier application Serial Number 104,416 filed June 19, 1916, entitled "Time fuse for artillery projectiles," 45 and contains the inventions set forth and claimed in said application, together with further improvements hereinafter particularly set forth.

The drawings illustrate an operative embodiment of the invention, and therein—

Figure 1 shows a complete fuse, with the

base and cap or setting member thereof in section and the mechanical parts in elevation.

Fig. 2 is a plan view of the fuse mechanism.

Fig. 3 is a plan view of the parts located below the timing disk, a portion of such parts being broken away.

Fig. 4 is a vertical section on line 4—4 of Fig. 3.

Fig. 5 is an elevation of the frame of the fuse mechanism, with the moving parts of the mechanism removed.

Fig. 6 is an elevation of the coupling between the setting member and the timing disk.

Figs. 7, 8, and 9 are plan views of the parts of the mechanism below lines 7—7, 8—8, and 9—9, respectively, of Fig. 4.

Fig. 10 is an elevation of the regulator for the time mechanism.

Fig. 11 is a longitudinal section of the same on line 11—11 of Fig. 10.

Fig. 12 is a cross section on line 12—12 of Fig. 11.

Fig. 13 is a sectional view of the hammer and trigger mechanism represented on an enlarged scale, taken on line 13—13 of Fig. 8 looking in the direction of the arrows, the same being shown in cocked position.

Fig. 14 is a similar view of the same parts in the released position.

Fig. 15 is an elevation of this mechanism as viewed from the right of Fig. 8.

Fig. 16 is a fragmentary view showing in elevation the stop for preventing running of the time mechanism.

Fig. 17 shows the stop in its released position.

The same reference characters designate the same parts in all the figures.

The fuse as a whole comprises a base 21, a cap or setting member 22, a time mechanism shown as a whole at 23 in Fig. 1 and 100 including an adjustable timing disk 24, and a coupling 25 between the setting cap 22 and the timing disk. The base 21 is adapted to be mounted upon a projectile and may be constructed in any manner which permits of 105 being so mounted. As here shown it is made as a screw plug having external threads 26 by which it may be screwed into a suitably formed opening in the projectile. The cap 22 is shown as a sheet metal cup, inverted, 110 formed with its rim inwardly offset and provided with a lip 27 which enters a recess in

the base 21 and is held therein by a lock 28, the same being conveniently a ring or wire lying partly in a groove in said flange and partly in a complementary groove formed 5 in the adjacent surface of the base. Thereby the cap may be rotated relatively to the base, without becoming detached therefrom, in order to set the timing mechanism to accomplish the detonation of the shell at a 10 given instant.

The timing mechanism, timing disk, and the hammer and trigger mechanism are all mounted in a frame which is shown particularly in Figs. 1 and 5 and comprises a bottom plate 29, a top plate 30 and an intermediate plate 31; the top plate being supported from the bottom plate by three (more or less) posts or pillars 32 and the intermediate plate being similarly supported by posts or pillars 33. These pillars are suitably secured in the bottom plate, and the top and intermediate plates are detachably secured thereto by screws 34 (Fig. 3) and 35 (Fig. 8). This frame is a structural unit having extreme strength and rigidity, which supports all the moving parts, including the hammer and trigger mechanism. It is suitably mounted on the fuse base and secured thereto, and is inclosed by 30 the cap 22.

The hammer and trigger mechanism comprises a hammer or firing pin 36 mounted so that it may move endwise in bearings in the top and bottom plates, a locking or trigger bar 37 having a trigger arm 38, formed preferably as a slender pin set at one end firmly in said bar, and a releasable detent lever 39 which is controlled by the timing disk 24. On the hammer is a flange 40 or shoulder 40 against which bears a spring 41, the latter being preferably coiled around the shank of the hammer in helical form and reacting against the top plate 30, the end which thus bears on the plate being 45 contained in an annular groove 41^a surrounding the bearing for the hammer shank, said groove being provided in order to give room for a greater length of spring than can be contained between the face of the plate and 50 said flange. This flange or shoulder rests, when the hammer is cocked, on a shoulder 42 of the trigger bar, which holds the hammer so that its point is retracted from the cavity 420 wherein a percussion cap is placed, the 55 spring 41 being then compressed. The trigger bar has trunnions 43 at its ends which lie in separated bearing sockets in uprights 44 on a chair 45 which is secured to the bottom plate 29 by a screw 46 or otherwise. The shoulder or hammer abutment 42 is formed between the trunnions by cutting away the trigger bar on one side so as to leave a surface which preferably passes through the axis of the trunnions, and is 60 preferably perpendicular to the line in

which the hammer is pressed by spring 41, such axis being transverse to said line. It will be seen that the shoulder 42 forms one arm of a bell crank lever of which the pin 38 is the other arm, and that by virtue of 70 the construction last described, said shoulder 42 may extend in a radial plane all the way to the axis of the trigger bar, and the latter may be so placed that its engagement with the flange shoulder or projection 40 of the 75 hammer is at any desired point between the outer edge or end of shoulder 42 and the axis of the bar. Thereby the bar may withstand the force imposed on it by the inertia of the hammer at the time of firing (that is, the 80 set back of the hammer), and the pressure transmitted thereby through the arm 38 at that time is not great, wherefore such arm may be made small and light. The cut away part of the bar which forms the shoulder 85 42 is otherwise so shaped that, when the trigger bar is turned to the position shown in Fig. 14, the projection 40 may fall freely away from it.

It will be observed that the axis of the 90 trigger bar is substantially radial to the axis of the fuse, as shown in Figs. 7 and 8, the latter axis being the geometrical center of the plates, and coinciding with the axis of the shell when the fuse is placed thereon. 95 This is an important feature, the value of which will be presently explained. The arm 38 is a rod or pin set into the trigger bar and of such length that when it is in the upright position, shown in Figs. 1 and 13, 100 it projects somewhat above the upper face of the plate 30, but not as far as the under surface of the timing disk 24.

The release lever 39 lies upon the upper face of the plate 30, to which it is connected by a pivot stud 47, and the plate supports the entire lever, its edge adjacent thereto having an outline approximately coincident with the outer edge of the lever. Said lever has two arms, on one of which is a shoulder 48 crossing the path in which the trigger arm 38 moves from the cocked to the releasing position, and on the other of which is a finger 49 crossing the plane of the timing disk, as shown in Fig. 1, and bearing 110 against the edge of the latter, thereby holding the shoulder 48 in the position shown in Figs. 2 and 3, in which said shoulder obstructs the arm 38. The end of finger 49 overlies the edge of the timing disk and thus makes impossible any such springing or bending up of the disk which is of thin sheet metal and therefore flexible, as would permit the finger to pass under it, and so possibly permit release of the hammer at the 115 wrong time. This release lever is of light stock, being conveniently made of a stamping punched out of sheet steel, and being therefore of equal thickness at all points. Its two arms are of such mass, and their 120 125 130

masses are so distributed, that the centrifugal forces acting on both arms in consequence of the spinning motion of the shell in flight are balanced on opposite sides of 5 the fulcrum. In other words, the product of the mass of the arm by the distance of its center of gravity from the pivot 47 is the same as to both arms. Thus centrifugal force has no excess tendency either to press 10 the finger 49 against the timing disk or to hold the shoulder 48 across the path of the trigger arm 38, wherefore neither the timing disk nor the trigger is impeded in its movement by the lever.

15 This shoulder is inclined to the plane in which the trigger arm moves, and consequently the pressure of the hammer spring transmitted through the arm tends to displace the shoulder, and it has that effect, 20 moving the same clear of the arm, when the detent lever is permitted to move by the arrival of the timing disk in a certain position. The edge 50 of the lever adjacent to the shoulder is so disposed as to clear the path 25 of the trigger arm when the lever is thus displaced.

That part of the top plate 30 which supports the lever is cut away, providing a channel 51 to receive and guide the end of 30 the arm 38, such channel being of course in the plane of movement of the arm, which is perpendicular to the axis of the trigger bar and thereby substantially squarely across the line in which centrifugal force 35 acts on the trigger arm since the trigger bar is approximately radial to the fuse axis. The outer boundary of the channel 51 thus serves as a retainer for the trigger arm, preventing it from being distorted or displaced 40 by centrifugal force.

When the time mechanism is in motion, the timing disk 24 is rotated thereby in the direction of the arrow in Fig. 2. A notch 52 is provided in the edge of the disk and is 45 adapted to admit the finger 49 when arriving opposite the same, thus permitting such movement of the detent lever as will carry the stop shoulder 48 clear of the trigger arm, whereby the trigger mechanism is 50 tripped and the hammer is allowed to strike. This disk is mounted on a shaft or staff 54, hereinafter called the "main" or "center" staff which has bearings in the 55 top and intermediate plates 30, 31, its bearing in the latter being a step bearing. Engagement between the staff and disk is frictional, the staff being tapered and the sleeve or hub 55, to which the disk is secured, having a tapered hole to fit it. The latter is 60 held securely enough so that it will not slip under ordinary accidental shocks, by means of a nut 56 screwed upon the end of the staff, and a spring washer 57 between the nut and the disk, having arms which bear 65 on the latter; but this engagement is loose

enough to permit adjustment of the timing disk by the setting cap through the coupling member 25. Upon firing the gun in which the shell carrying the fuse is loaded, the set back due to the inertia of the disk and its 70 hub under the force suddenly applied by explosion of the propelling charge, forces the hub tightly upon the staff.

The coupling 25 between the timing disk and setting cap is a tongue of flexible material which is carried by the setting cap and the end of which is so curved or bent as to cross the plane of the timing disk and pass through an opening 58 in the latter; said tongue being preferably of sheet metal 80 of width great enough to provide such stiffness as is required to transmit movement from the cap to the disk for setting, and of a thickness so slight that it may be flexed in the manner presently explained. 85 This disposition of the coupling enables the edge or rim of the disk to cross the opening 58 uninterruptedly, whereby such opening may be located in any part of the disk without reference to the position of the 90 detent finger 49, and the entire circumference of the disk is available for setting. It is thus possible to set the disk so that it must rotate almost 360° before it releases the trigger mechanism. The engagement of 95 the coupling is positive with each side of the opening 58, whereby the timing disk can be turned in either direction by rotation of the cap. Disconnection of the coupling is effected by set back on discharge of 100 the gun, the coupling being confined and guided between the wall of the cap and a bridge plate or holder 59, secured thereto, which has a lip 60 underlying the curved part of the coupling and is sufficiently rigid 105 not to be distorted by set back. A weight 61 is connected to the outer end of the coupling and is of such mass that it suffices under set back to withdraw the tongue from the opening 58, pulling it over the bridge 59 and 110 overcoming the resistance to such movement due to the bend in the tongue. Thus as soon as the shell is fired from the gun, the timing disk is released from the setting cap and left free to rotate with the time mechanism, with which it has at the same time become firmly connected by wedging of the hub 55 on the tapered part of staff 54, as 115 already described.

The motive force for the timing mechanism here shown is furnished by a spring 62 coiled as a flat spiral within a cavity in the top plate 30, over which is arranged a cover 63 secured to the top plate. The outer end of this spring is fastened to an 120 annular winding wheel 64 having teeth which are accessible through a hole 65 in the cover plate to be engaged by a toothed winding key. A spring-pressed click or pawl 64^a engaging the teeth of the wheel 130

holds the spring in wound-up condition and sustains its reaction. The inner end of the spring is connected to a collar 66 on the staff 54. The spring is one of several possible motive elements which may be used to drive the timing member, and I do not restrict the invention to this particular motive means. It is in my contemplation to employ such driving devices as a weight, 5 remaining relatively stationary while the shell rotates, or a fan rotated by the air resistance, or other possible means to propel the timing member. To regulate the speed of the mechanism there is provided a gear train comprising a gear wheel 66^a on the staff 54; a second wheel 67 having a staff 68 which passes through the intermediate plate 31, having its bearings in the bottom plate 29 said staff 68 in a potence 10 68^a so mounted upon the upper side of the intermediate plate 31 as to bring the upper bearing above the plane of the gear wheel 66^a, and carrying a pinion 69 in mesh with this wheel; a third wheel 70, to which is connected a pinion 71 in mesh with the wheel 67; an escape wheel 72 carrying a pinion 73 in mesh with the wheel 70; and an oscillative pallet 74 carrying pins 75 and 25 76 which obstruct the teeth of the escape wheel and are moved alternately out of the way of such teeth by the pressure exerted against them through the inclined sides of the teeth. The pallet is mounted on a staff 77 and is controlled by a spring 78 which 30 passes through said staff and is wedged therein, as shown in Fig. 9. One end of the spring is confined by stops 79 and the other end is engaged with a regulator 80, adjustable along the spring to alter its 35 effective length, and thereby the force which it exerts to return the pallet after each displacement thereof, and so the speed of oscillation of the pallet. This regulator is an extension at one side of a plate 81, which is 40 formed as a bridge with its ends turned down so as to rest on the bottom plate, and this extension has a notch 82 receiving the spring. A regulating screw 83 passes through the turned down ends of the bridge 45 plate and is threaded into a stud 84 fixed in the plate 29. A groove 85 in the head of the screw receives parts of the bridge plate 81 whereby the latter is compelled to move endwise with the screw, although the 50 screw has freedom of relative rotation. This regulator is held upon the bottom frame plate by a cover plate 86, which is secured to the frame plate by a screw 87, and it is guided by a groove 88 in said bottom 55 plate into which a lug 89 on the bridge plate projects.

Both the main staff 54 and the escape pallet 74 are mounted in the axis of the fuse in order to avoid the disturbing effects

of centrifugal force set up by the spinning 65 of the shell in flight. This arrangement brings the main staff and the pallet staff in line, the former being entirely above the intermediate plate, and the latter being between the intermediate and bottom plates. 70 In order to protect the pallet staff against injury by the setback force of the center or main staff and the parts which are mounted thereon, the upper pivot bearing of the pallet staff is formed, not in the intermediate plate, but in a bridge or spider 75 90 supported by the posts 33 below the intermediate plate, and slightly separated from the latter by interposed washers.

This spider, being separated from the 80 intermediate plate, is not affected by the force applied upon the latter by the inertia of the main staff, and it is further supported by posts 92, 93 set upon the bottom plate at opposite sides of the pallet. These 85 posts have shoulders which underlie the spider, and reduced necks which pass through the spider and bear against the under side of the intermediate plate.

The wheels of the time train are at one 90 side of the axis of the fuse and mainly outside of a line joining the two adjacent supporting pillars 33 of the intermediate plate. The peripheral part of that plate which 95 therefore overlies the train wheels and provides the bearings for the same is prevented from springing under set back by a suspender 94, provided by a screw which is passed through the top plate and is threaded into a tapped hole in the intermediate plate. 100 This screw may be one of those which hold the cover plate 63 of the main spring cavity in place.

The frame, constructed as hereinbefore described, combines the advantages of 105 strength and rigidity with comparative lightness, accessibility, and low cost of manufacture. The three plates and the spider may be produced by punching from sheets or plates of metal, and the various posts 110 may be cut from rods of the required diameters, all these parts being thus produced with the minimum of machine work and labor cost. This form of construction enables each of the parts to be designed with 115 exactly the proper mass of material, and no more, necessary to furnish the required rigidity, whence it follows that the frame as a whole may be trimmed of all excess weight and thus built with the minimum 120 of weight in proportion to the rigidity required to meet the tests of service.

The time mechanism is prevented from 125 running until after the shell has been fired, by means of a stop arm 95 carried by the staff 54, and a stop 96. This stop has a collar 97 contained in a complementary notch in the end of the arm 95, preventing the lat-

ter from moving in either direction; and it has shanks 98 and 99 which are guided in openings in the plates 29 and 30; being adapted to move endwise therein in a line 5 approximately parallel to the axis of the fuse. A part of this stop is provided with an inclined shoulder 100 which is engaged with spring jaws 101 arranged to hold the stop in engagement with the arm, as shown 10 in Fig. 16. This inclined shoulder or conical surface is adapted to spread the spring jaws apart and slip between them, under the fore of set back, wherefore when the shell is fired the stop passes from the position 15 shown in Fig. 16 to that shown in Fig. 17, wherein the shoulder 97 lies below the stop arm 95. On the upper shank 98 there is a shoulder 102, the end of the shank beyond this shoulder being reduced in diameter, and 20 when the stop is displaced as above described, this shoulder is brought below the under surface of the top plate 30. Thereupon centrifugal force, due to the rotation of the shell, moves the upper end of the 25 stop outward until its reduced end strikes the side of the hole in the plate 30, and the shoulder 102 is carried under the under surface of this plate, preventing the stop from rebounding. Thus a positive lock is provided 30 which retains the stop in the releasing position.

A further safeguard to insure against accidental detonation of the fuse is provided in the form of a block 103 resting on the 35 bottom plate and mounted to turn about a pivot stud 104. The edge of the block lies under the shoulder 40 of the hammer, and it is normally held in the position shown in Figs. 7, 8, and 13 by a light spring 105 40 which is coiled about the stud 104, one end of the spring being secured to that stud and the other end bearing against a shoulder on the block. A part of the block then bears against one of the pillars 33. In the edge 45 of this block near that part which thus underlies the hammer is a recess 106 adapted to be brought beside the hammer and so formed as to admit the shoulder 40. This block is unbalanced, its center of gravity being between the pivot stud and the hammer, where- 50 by centrifugal force due to the rotation of the shell moves it until the recess 106 is beside the hammer, a shoulder 107 on the block arresting it in this position by coming in contact with the adjacent pillar 33. Thus 55 when the trigger mechanism is thereafter tripped, the hammer is free to pass and strike the detonating cap; but up to the time when the shell has actually been fired from the gun and thereby set in rotation, the block 103 stands in the way of the hammer and prevents it from striking the cap even though the trigger mechanism should accidentally be released. The block is of so 60 great mass and the spring 104 so light that

the block is certain to remain in the releasing position as long as the shell continues in flight.

It will be appreciated from the foregoing that immediately upon firing of the gun in 70 which the shell equipped with my fuse is loaded, the coupling between the setting member and the timing disk is disconnected and the stop which prevents running of the time mechanism is displaced, and is at once 75 locked so that it can not rebound into position for again obstructing the mechanism, whereby the mechanism commences to run, driving the timing disk in the direction indicated. At the same time the block 103 is 80 displaced so as no longer to obstruct the hammer. When the time mechanism has run for a given length of time, determined by the previous setting of the timing disk, the notch 52 arrives opposite to the finger 49 of 85 the release lever, allowing such finger to enter, and the abutment 48 to be displaced from the path of the trigger arm 38. The latter, being actuated by the hammer spring 41, pushes this abutment out of the way, and 90 swings over, permitting the locking shoulder of the trigger bar to be displaced out of the way of the hammer projection 40, thereby 95 permitting the hammer to strike and detonate the cap.

The terms used in the foregoing description have been adopted solely for convenience and without intent of limiting the protection which I claim to parts corresponding strictly with any specific definitions of such terms. Neither do I limit the invention to the precise relative positions of the parts as shown, but include within the protection hereinafter claimed corresponding elements of all forms and descriptions having any 100 desired relationship, provided only they co-operate to produce the desired results in substantially the manner pointed out in the claims. The terms denoting relative position, such as "horizontal," "vertical," 105 "above," "below," etc., have been used with respect to the particular position of the fuse shown in the drawings, the axis of the same being represented as vertical and the plates as horizontal. In actual service the axis of 110 the fuse is in the line of initial flight of the shell, and the force of set back acts in this line, while centrifugal force acts in a plane perpendicular to this line. For the purposes of this description, therefore, the terms 115 "vertical" and "horizontal" may be considered as meaning respectively the line of initial flight and the plane in which centrifugal force acts, whatever may be the relation of such line and plane to the horizon. 120 The following claims are to be construed in the light of the foregoing definitions.

What I claim and desire to secure by Letters Patent is:

1. In a time fuse, a firing member, a time 130

controlled mechanism for governing the operation of said member, an adjustable timing element associated with said mechanism and constructed with a recess located within 5 its periphery, a setting member movable to shift and thereby adjust said timing element, and a coupling carried by said setting member having one end offset from said member projecting across the plane of movement of the timing element into said recess 10 for transmitting the movement of said member to said element, said coupling being guided to move by inertia on firing in a direction such that its offset end is withdrawn 15 from said recess.

2. A time fuse comprising in combination a driving mechanism, a timing disk engaged with said driving mechanism to be driven thereby and adjustable relatively thereto, 20 said disk having an opening within its edge, a setting member concentric with said timing disk adjustable about the common center, and a coupling of flexible material carried by the setting member and being curved 25 and located to carry its end across the plane of said timing disk and into said opening, said end being withdrawn from the opening by inertia under the shock of firing.

3. A time fuse comprising in combination, 30 a driving mechanism, a timing disk engaged with said driving mechanism to be driven thereby and adjustable relatively thereto, said disk having an opening within its outer edge, a setting member concentric with said 35 timing disk adjustable about the common center, a coupling of flexible material lying alongside the setting member and being curved to carry its end around the edge of the timing disk and into said opening, and 40 a relatively rigid guide secured to the setting member supporting said coupling; the coupling being so weighted that it is dislodged by inertia on firing and is moved along the guide, withdrawing the end of the 45 coupling from said opening.

4. In a time fuse for an explosive projectile, the combination of a base, a time mechanism supported on said base and including a controlling disk, a cap rotatably 50 mounted on the base, and a coupling member comprising a piece of relatively soft metal mounted on the cap and having one end extending therefrom and bent substantially into the plane of the controlling disk 55 to engage the same normally, and to be removed from such plane by inertia when the projectile is fired from the gun, whereby to release the time mechanism.

5. In a time fuse the combination of a 60 timing member, an adjustable setting member, and a coupling between said setting member and timing member, said coupling being a bar of flexible material having a curved end portion passing into engagement 65 with the timing member, and being so dis-

posed that said end portion is flexed and withdrawn from engagement with the timing member by the action of inertia on firing.

6. In a time fuse the combination of a 70 setting member, a timing element, said setting member and timing element being movable in approximately concentric relation, a holder connected to said setting member, and a coupling device of flexible material 75 supported by said holder having one end extended on a curve into locked engagement with said timing element, and the other end being weighted, whereby the inertia of the latter end upon firing is adapted to withdraw the first-named end from engagement with the timing element.

7. In a time fuse, a hammer and trigger mechanism comprising a spring-impelled hammer having a cocking shoulder, a trigger bar mounted to turn about an axis transverse to the direction in which said shoulder is adapted to move, and having a surface crossing the path of said shoulder when the hammer is cocked, means supporting said 85 bar at opposite sides of the part thereof at which it is engaged by said shoulder, whereby the shoulder is enabled to bear on the bar at a point close to its pivot axis, a trigger arm connected to said bar, and means 90 for releasably holding said arm in the position for obstructing said hammer.

8. A time fuse comprising in combination a firing hammer, a trigger mechanism for holding said hammer in cocked position and 100 having a release arm, a holding lever having an abutment arranged to engage said release arm when the latter is in cocked position and extending across the path wherein said arm moves upon release of the hammer, and a 105 timing member having a surface engaging a portion of said holding lever to retain the same in trigger-holding position, said timing member being connected with a time mechanism and having a recess arranged to 110 permit entrance of a part of the holding lever when in a certain position, whereby said lever is enabled to be displaced by the trigger arm, releasing the latter.

9. In a time fuse, a hammer mechanism 115 comprising a spring impelled hammer having a projection, a trigger bar rotatably mounted on an axis transverse to the line in which pressure is exerted by said projection and having a shoulder portion arranged at one side of its axis of rotation and between its ends to support said projection against thrust of the spring when said shoulder is approximately perpendicular to the line of movement of said projection, a time mechanism, and automatically releasable means controlled by said time mechanism for holding the trigger in the position described against the thrust of said spring.

10. In a time fuse, a hammer mechanism 130

- comprising a firing hammer having a projection at one side of its line of movement, a spring pressing said hammer toward the firing position, a trigger comprising a bar 5 having separated trunnions by which it is pivoted beside said hammer on an axis transverse to the movement of the latter and at one side of the path of said projection, and having a surface at one side of its pivot 10 axis sustaining said projection against the pressure of the spring when placed in the cocked position with such surface substantially perpendicular to said path, an arm on said trigger, a holding lever having an 15 abutment to engage said arm when the trigger is in the cocked position and to extend across the path wherein said arm moves into releasing position, and time controlled means for retaining said lever in such position and permitting its release of the trigger 20 arm at a definite time.
11. A mechanical time fuse comprising a spring actuated firing member having a cocking projection, a bar having separated 25 trunnion elements and a flat surface between said elements substantially parallel to the line joining said elements, a support for said bar having bearings for said trunnions and arranged to hold said flat surface across the 30 path of said cocking projection when said firing member is cocked, the bar being adapted to be turned to release said firing member, a trigger arm connected with the bar, and time controlled means normally engaging 35 said trigger arm to hold the same and the bar in the position which obstructs the firing member, and adapted to release the same at a predetermined time after firing the projectile from the gun.
- 40 12. In a time fuse for shells the combination with a spring pressed hammer, a trigger bar supported at separated points to turn about an axis passing through said points, having a portion at one side of said 45 axis and between said points underlying a part of the hammer to hold the same in cocked position and having an arm, a detent interposed in the path of movement of said arm when the latter is in cocked position 50 having an abutment for said arm crossing the path of movement of the latter at an inclination to such path, whereby the force applied by said arm tends to displace said detent, and a mechanically driven timing 55 member holding said detent in place provided with means for releasing the detent at a given time.
13. A hammer and trigger mechanism for fuses comprising a movable hammer having 60 a projection, a spring acting on said hammer to move the same from cocked position to firing position, a trigger stop extending across the path in which said projection moves and having a surface which obstructs 65 and engages said projection when the ham-
- mer is cocked, means at opposite sides of said surface in a line substantially parallel thereto pivotally mounting said stop in a position such that the point engaged by said projection is near said line and between 70 such line and the hammer, whereby the hammer tends to turn said stop and pass the same, and an arm connected with the stop adapted to be held in the position which causes said surface to obstruct said shoulder. 75
14. A mechanical time fuse comprising a frame having plates and pillars connecting and spacing said plates, a spring impelled hammer mounted in said frame, a trigger mechanism for holding said hammer 80 cocked adapted to be moved to release the hammer and including an arm, said arm being movable in a plane intersecting one of said plates, and said plate having a slot to receive the arm, both the slot and the plane 85 in which the arm moves being otherwise than radial to the axis of the fuse, said arm when occupying said slot projecting beyond the outer surface of the plate, a release lever mounted on the outer face of 90 said plate having a part to cross said slot and hold said arm therein, but adapted to withdraw from the arm when permitted, and a motor driven timing element movably mounted adjacent to said lever, holding the 95 lever in the position described and permitting its withdrawal to release the trigger arm when said timing member reaches a given position.
15. In a mechanical time fuse adapted to 100 be carried by a spinning shell, a frame, a spring impelled hammer, a pivotally mounted trigger for holding the hammer cocked, said trigger having an arm, a time-controlled means for holding said arm in the 105 hammer-cocking position and for releasing the arm, said arm being movable in a plane other than radial to the axis of the fuse, and the plate having means for preventing displacement of said arm by centrifugal force. 110
16. In a time fuse including a frame adapted to be supported on a rotatable projectile in a given manner, a firing hammer movable in a direction parallel to the axis about which said frame is intended to rotate, and having a laterally projecting shoulder, a trigger bar having separated bearing portions arranged to turn upon a pivot line which is substantially radial to 115 said axis, said bar having a surface between 120 its bearing points adapted to lie across the path of said projection when the hammer is cocked and to be moved by turning of the bar out of said path, an arm on said bar, a detent for engaging said arm to hold the 125 bar in the hammer cocking position, a chronometric mechanism mounted in said frame, and a timing member driven thereby constructed to effect release of said trigger arm at a predetermined instant. 130

17. In a mechanical time fuse, a spring-impelled hammer, a stop for holding said hammer in cocked position having a release arm, a pivotally mounted two-armed lever 5 formed with an abutment on one arm in the path of and obstructing said release arm, said lever having a finger on its other arm, and the product of the mass times the distance of the center of gravity of the arm 10 from the pivot being the same as to both arms whereby to equalize the turning moment of centrifugal force on the lever in opposite directions, a time mechanism, and a disk driven by said time mechanism against 15 the periphery of which said finger bears and in the periphery of which is a notch adapted to be entered by said finger so as to release the trigger arm.

18. In a time fuse, a time mechanism including a timing disk having a notch in its periphery, a two-armed lever mounted in a plane parallel to and near the plane of said disk having a finger on one arm which is arranged to bear on the peripheral part of 25 the disk, the arms of said lever on opposite sides of a line passing through the axis of the fuse and the fulcrum of the lever being equal to one another in the product of mass multiplied by distance of the center of gravity of the arm from the fulcrum, whereby to equalize the turning moment of centrifugal force acting at opposite sides of said line, a rotatably mounted trigger stop having a release arm movable in a path which 30 crosses a part of said lever in a plane transverse to the plane of the latter; and a spring-impelled hammer having a shoulder adapted to be engaged by said trigger stop to hold the hammer in cocked position, the 35 trigger release arm being then transverse to said lever, and the latter having an abutment crossing the path of said arm and so disposed that the pressure exerted by the arm tends to displace it from such path.

40 19. In a mechanical time fuse the combination with a spring-impelled hammer, of a rotative trigger bar having a locking shoulder to hold said hammer in cocked position and an arm projecting from said bar transverse to its axis of rotation, a driven timing member, and a release lever having two arms, one of which engages said timing member and the other of which is engaged by said trigger arm, said release 45 lever being so constructed that the centrifugal forces acting upon its arms on opposite sides of its fulcrum are substantially balanced, and the timing member having provisions for permitting, when in a certain 50 position, such movement of the release lever as to permit displacement of said abutment from the path of said trigger arm.

60 20. In a time fuse having a frame, a driven timing disk with a notch in its rim, a hammer, and a trigger for holding the

hammer cocked provided with a hammer-locking shoulder and a release arm, a release lever fulcrumed upon said frame and having a finger crossing the rim of said disk and adapted to enter the notch thereof, 70 said lever having a second arm provided with an abutment engaging the trigger arm when the latter is in cocked position and inclined to the plane of movement thereof whereby said arm is adapted to displace 75 said abutment from its path when the lever is otherwise permitted to move; said lever having its arms so disposed on opposite sides of a line joining its fulcrum with the axis of the fuse and so proportioned that 80 centrifugal forces acting on said arms are substantially balanced.

21. In a time fuse having a hammer and trigger mechanism and a time controlled mechanism for governing the operation 85 thereof, a stop for preventing running of said mechanism prior to the firing from a gun of the projectile to which said fuse is applied, said stop comprising a piece located to obstruct a portion of said time 90 mechanism and being displaceable from such location by set back, and having also locking means controlled by centrifugal force to prevent rebound into obstructing 95 position.

22. In a time fuse, a frame having plates, a time mechanism mounted in said frame including a rotating arm, hammer and trigger mechanism controlled by said time mechanism, and a stop having a part located 100 to arrest said arm and thereby prevent running of the time mechanism, said stop having shanks mounted in the plates of said frame and being movable endwise, and resilient jaws resisting such movement but adapted to be displaced to permit movement of the stop under set back, said stop having also capacity for lateral movement and having a shoulder movable by centrifugal force under a part of one of said plates to prevent 110 rebound of the stop into locking position.

23. In a time fuse according to claim 22 the stop characterized by shanks movable endwise in the frame plates, resilient jaws embracing one of said shanks, the latter having a conical surface adjacent to said jaws and adapted to be forced between them by set back, and the other shank having a shoulder arranged to be withdrawn from the frame plate adjacent thereto by set back 115 and to be carried under said plate by centrifugal force.

24. A mechanical time fuse comprising a bottom plate, a top plate, and an intermediate plate, pillars supporting said top plate and intermediate plate, a driven staff having bearings in the top and intermediate plates, a timing member carried by said staff, a gear train having bearings in the bottom and intermediate plates, an oscil- 120 125 130

lating escape device having one of its bearings in said bottom plate, a separate spider or plate having the other bearing for said escape device beneath the intermediate plate 5 and independent thereof, a firing hammer, and trigger mechanism for holding the same cocked, controlled and releasable by said timing member.

25. A mechanical time fuse comprising a top plate, a bottom plate, an intermediate plate, pillars supporting said top plate and said intermediate plate, a driven center staff in the axis of the fuse having its bearings in the top and intermediate plates, a timing 10 member mounted on said staff, a gear train having bearings in, and being arranged between two of said plates and geared to said center staff, an oscillative escape member mounted between the bottom and intermediate 15 plates in the axis of the fuse having pivots, one of which bears in the bottom plate, a separate bridge supported out of contact with said intermediate plate in which the other of said pivots bears, a spring 20 tending to hold said escape member in a central position, means by which one of the wheels of said train drives the escape member oscillatively, a firing hammer, and trigger mechanism for holding the same cocked, controlled and releasable by said timing 25 member.

26. A mechanical time fuse comprising a massive frame composed of a bottom plate, a top plate, pillars between the plates supporting the top plate, an intermediate plate within the circuit of said pillars, other pillars supporting said intermediate plate, a bridge supported from the bottom plate under said intermediate plate, a center staff 30 journaled in the top and intermediate plates in the axis of the fuse, an oscillative escape member journaled in the bottom plate and in said bridge, also in the axis of the fuse, a main wheel on said staff between the top 35 and intermediate plates, a time gear train between the bottom and intermediate plates, the first wheel of said train having a staff which passes through the intermediate plate, a pinion on said first wheel staff above the 40 intermediate plate meshing with said main wheel, a potence fixed on the intermediate plate having a bearing for said staff, the last wheel of the train being constructed and arranged to drive said escape member back 45 and forth, a timing disk on said main shaft, a spring impelled hammer, and trigger mechanism for holding said hammer cocked controlled by said timing disk.

27. A mechanical time fuse comprising a frame consisting of top, bottom, and intermediate plates with means holding said plates at given distances apart, a gear train mounted between said bottom and intermediate plates, an oscillative escape device 50 operable by the last wheel of said train hav-

ing pivots one of which has its bearings in the bottom plate, a bridge beneath and separate from the intermediate plate having the bearing for the other pivot of said escape device, a main staff passing through the top 70 plate and having a bearing in the intermediate plate, a wheel on said staff, a pinion in mesh with said wheel and connected to the first wheel of the aforesaid train, the last named wheel having a staff passing through 75 the intermediate plate, a timing member mounted on said main staff, and hammer and trigger mechanism controlled by said timing member.

28. In a mechanical time fuse, a frame 80 comprising plates and massive pillars interposed between said plates, a time regulated mechanism mounted in said frame, a staff controlled as to its speed of rotation by said mechanism, passing through one of the 85 plates, a timing disk carried by said staff and rotatable therewith, a release lever pivotally mounted and substantially lying on one of said plates having a portion to engage the timing disk and having a release 90 portion, a spring actuated hammer, and a trigger for holding said hammer cocked provided with a release arm engaged with the release portion of said lever and adapted to disengage itself therefrom when said timing disk occupies a given relation to the lever.

29. In a time fuse, a frame comprising a bottom plate, two sets of pillars or posts mounted thereon of different heights, a top 100 plate mounted upon the pillars of greater height, an intermediate plate and a bridge mounted upon the pillars of less height, said bridge being below the intermediate plate and separated therefrom, a main staff 105 having bearings in the top and intermediate plates in the axis of the fuse, an oscillative pallet having bearings in the bottom plate and bridge in the same axis, a gear wheel mounted on said staff, a pinion meshing 110 with said gear wheel, a staff for said pinion passing through the intermediate plate having a bearing in the bottom plate, a potence on the intermediate plate having a bearing for the opposite end of the latter staff, a 115 gear wheel on the latter staff, and a time train between the bottom and intermediate plates driven by the last named wheel and including an escape wheel coöperating with said pallet.

30. In a time fuse according to claim 29, the frame being further distinguished by a recess in the top plate, a coiled spring in said recess connected at one end to said center staff, a winding wheel to which the 125 other end of said spring is connected, and a timing member mounted on said center staff.

31. In a mechanical time fuse, a frame comprising top, bottom, and intermediate plates, pillars supporting said top and in- 130

- termediate plates upon the bottom plate, a time train located between the bottom and intermediate plates and having its bearings therein, a center staff having bearings in 60
 5 the top and intermediate plate and resting on the latter, and a suspension member depending from the top plate and engaged with the intermediate plate over said time train to sustain said portion of the intermediate plate against springing under the forces acting when the shell equipped with the fuse is fired from a gun.
32. A frame for a mechanical time fuse according to claim 31 distinguished by a 65
 15 bridge beneath and separated from the intermediate plate, an oscillative pallet having its bearings in said bridge and in the bottom plate in substantial alinement with the main staff but relieved of pressure from said
 20 main staff under set back by the separation of the bridge from the intermediate plate.
33. A frame according to claim 32 distinguished further by posts mounted upon the bottom plate on opposite sides of the pallet 70
 25 and supporting said bridge at points relatively near the pallet.
34. A frame comprising a bottom plate, pillars mounted on said bottom plate, a top plate mounted on said pillars, a second set 75
 30 of pillars shorter than the distance between said plates and mounted on the bottom plate, an intermediate plate and a bridge supported on the last named pillars, with a space between them, and posts rising from
 35 the bottom plate on opposite sides of the center thereof and supporting said bridge.
35. A frame according to claim 34 distinguished by the fact that said posts are formed with shoulders supporting the 80
 40 bridge and with reduced ends which pass through the bridge and support the intermediate plate.
36. A frame according to claim 35 distinguished further by a suspender depending from the top plate and engaged with the intermediate plate near its rim between two of the supporting pillars thereof to support that part of the intermediate plate 85
 45 against distortion under set back.
- 50 37. In a mechanical time fuse, a frame composed of plates and pillars connected together as a structural unit, time mechanism mounted on said frame, a spring impelled hammer mounted and movable on the frame, 90
 55 a chair independent of said frame and secured to one of the plates thereof adjacent to the hammer and provided with separated uprights, and a trigger bar journaled in said uprights and having its intermediate part extending near the hammer and provided with a shoulder adapted to obstruct a part of the hammer to hold the latter in cocked position.
38. In a time fuse, the combination with a frame, time mechanism and a hammer, of 95
 a chair provided with separated standards having open notches in their upper ends forming journal bearings, and a trigger bar provided with journals adapted to occupy and turn in said bearings, the part between 100 the bearings being arranged across the path through which a portion of said hammer moves in striking, whereby to hold the hammer cocked.
39. A time fuse comprising a driven shaft, 105
 a time train driven by said shaft for regulating the rate of rotation of the latter, an oscillative escape member driven by a wheel of said train, plates holding said shaft, time train, and escape member, a spring connected to said escape member lying against the surface of one of said plates, a regulator for said spring comprising a slide having a fork embracing said spring and being supported on and being movable over 110
 the last-named plate, a screw engaged with a part of said slide, and a holder fixed to said plate into which the screw is rotatably threaded, a hammer, a trigger mechanism for said hammer, and a release means driven by said shaft for releasing the trigger to permit operation of the hammer.
40. A time fuse comprising a base plate and a top plate, a driven shaft, a time train geared to and driven by said shaft for regulating the speed of the latter, an oscillative escape member driven by one of the wheels of said train, a spring controlling said escape member, a regulator for said spring comprising a screw, a post mounted in the 115
 90 base plate into which said screw is threaded, a slide having foot portions resting on said plate, in one of which the screw is confined so that it may rotate without moving endwise, a forked projection on said slide embracing the spring and movable along the same, and the base plate having a groove parallel with the spring in which a projection on one of said foot portion enters, and a guard fixed to the base plate overlying 120
 105 and holding the regulator slide in place; hammer and trigger mechanism, and release means for said mechanism operated and controlled by said shaft.
- In testimony whereof I have affixed my 125
 110 signature.

OLOF OHLSON.
